ABSTRACT

Imaging methodology and materials are disclosed utilizing cyanine dye coordinate structures of the type:

where M is a heavy metal ion, and D and preferably D' are photographic developer structures. Actinic radiation for the said coordinate structures reduces the metal ions and partially oxidizes the fragments D, D', whereby image development of members sensitized with said coordinate structures can be effected by chemically disrupting the NH-C bonds.

8 Claims, No Drawings

IMAGING METHOD AND MATERIALS

This application is a continuation-in-part of my co-pending application, Ser. No. 52,981, filed July 7, 1970 now abandoned.

This invention relates generally to imaging technology, and more specifically relates to methods and materials for photographic imaging of light patterns.

In conventional black and white photographic methodology, photosensitive compounds — typically silver salts — are present in a light sensitive emulsion, and following exposure to the light pattern to be recorded development of the latent image is achieved through use of an external developing agent, which agent upon application to the said emulsion effects a reduction-oxidation reaction at exposed points therein to reduce the said silver to its metallic form.

Although the conventional methodology set forth is in most widespread use, there are certain inherent deficiencies in such processes which yet limit their usefulness. Such deficiencies principally derive from the use therein of the aforesaid external developing agents. Because of the requirement to employ these agents to develop the latent photographic image, relatively sophisticated techniques and lengthy procedures need be used to develop conventional exposed film, and in consequence the vast bulk of such processing is indeed performed by industrial laboratories or the like which possess the sophisticated expertise desirable for assuring uniform quality in developed products. The high volume industrial-type processor is similarly favored in comparison to the amateur or small scale processor in that the shelf life of these external developing agents is limited and the freshness of reagents is an important consideration in assuring high quality results.

The use of the aforementioned external developing agents has yet another important detrimental effect on image quality. In particular it is necessary during the development process for the said agents to diffuse through the sensitized layer to the situs of the latent image, and it is often found in consequence that resolving properties of the imaging layer are adversely affected by such diffusion process.

In accordance with the foregoing, it may be regarded as an object of the present invention, to provide processes and materials which vastly simplify the processing techniques for developing images in an exposed photographic member.

It is a further object of the present invention, to provide imaging methods and materials which enable development of latent images in exposed members by simple heat, infra-red or radiant energy processing techniques, or by simple treatment of said member with a buffered aqueous alkaline solution.

It is another object of the present invention, to provide an imaging member of high light sensitivity and displaying excellent image resolution.

Now in accordance with the present invention, the foregoing objects, and others as will become apparent in the course of the ensuing specification, are achieved in an imaging system based upon use of cyanine dye coordinate structures of the general type:

5

2

where n is an integer, M is a heavy metal ion such as silver (which ion may also be thus complexed as the metal halide), and D and preferably D' are photographic developer structures such as a para amino phenol, some in their oxidized form, which form with the guanidine-type

15

20 structure a cyanine dye. Where both D and D' are developer structures, D and D' need not be identical. D' may, for example, be of a different type to provide a mixture of developing agents, thereby producing a super-additive effect in the developing process.

25 The entire structure (1) is effectively a cyanine dye sensitizer and when light of appropriate wavelength (actinic radiation) strikes the structure (1) and is absorbed, the dye molecule donates electrons to the metal ion, reducing such ions and partially oxidizing the reducing agents represented by D — and in preferable embodiments by D' . In a typical process, M is silver and following light exposure heat and/or a buffered alkaline solution is applied to the exposed image. The heat (of the order of 100° to 200°C) or alkaline solution (pH of the order of 10 to 13) disrupts the $NH-C$ bonds in the said

35

40 structure, releasing the partially oxidized developing agents D , D' and unoxidized developing agents in areas not struck by light. Development is rapidly completed, and the image is washed and fixed in a conventional silver solvent, i.e., acid fixer or hypo bath.

45 The organic salts utilized in accordance with the invention are, in an organic structural sense, dye sensitizers classified as cyanines, azacyanines, carbocyanines, hemicyanines, and merocyanines, and all contain heat or alkaline fracturable members which when released act as photographic developers or reducing agents. In the structure (1) at least the fragments D will constitute such a developer agent; the D' fragment need not in general be a developing agent, but must only be capable of forming a cyanine dye with the guanidine-type

55

60 portion of structure (1) and possess the additional characteristic that it not dye couple with the fragments of oxidized developing agent D released from said guanidine-type structure. In preferable embodiments of

the invention, however, D' will in fact be a developing agent: preferably thus, D will be a para amino phenol or para phenylene diamine while D' will be selected from the oxidized para dihydroxy benzenes. Representative structures for these organic salts include:

(2)

and

(3)

both structures being of the general type shown at (1). It will be apparent to those skilled in the art of photographic chemistry that the portions of structures (2) and (3) corresponding to D and D' in structure (1) are well-known photographic developers, and D and D' may in fact comprise any of numerous other known developers including by way of further examples:

Typical structures for D:

type $\text{HO}-(\text{CH}=\text{CH})_n-\text{NH}_2$:type $\text{H}_2\text{N}-(\text{CH}=\text{CH})_n-\text{NH}_2$ $\text{R}=(\text{CH}_2)_2\text{OH}-\text{CH}_2\text{OCH}_2\text{OH}-\text{CH}_2\text{C}_6\text{H}_4\text{SO}_3\text{H}-(\text{CH}_2)_2\text{CO}_2\text{H}$

Typical structures for D'

Type $\text{HO}-(\text{CH}=\text{CH})_n\text{OH}$ (in their oxidized state)Representative structure (2), above, is seen to be of 15 the general form:

Provided only that the groups corresponding to D, D' in structure (1) are photographic developers, the structure (4) can be even further generalized to:

where R = alkyl, aryl, H, CH_3 , C_2H_5 , $-\text{CH}_2\text{C}_2\text{H}_5$,
 40 $-(\text{CH}_2)_n\text{OH}$, $-\text{CH}_2\text{C}_6\text{H}_4\text{SO}_3\text{H}$, $-(\text{CH}_2)_n\text{CO}_2\text{H}$, $-(\text{CH}_2)_n\text{NHSO}_2$
 $-\text{CH}_3$, $-(\text{CH}_2)_n\text{OO}_2\text{SOH}$, $-(\text{CH}_2)_n\text{OC}_6\text{H}_4\text{SO}_3\text{H}$, $-\text{C}_3\text{H}_6\text{SO}_3\text{H}$,

45 $-\text{N}(\text{CH}_2)_2\text{O}$, and $-\text{CH}_2\text{CH}_2\text{OCH}_2\text{CH}_2\text{CH}_2\text{O}$

 $\text{R}' = -\text{OH}$, $-\text{NR}_2$ 50 $\text{R}'' = \text{R}$, $-\text{OR}$, $-\text{NR}_2$,55 Cl , Br ,$-\text{SO}_3\text{H}$, $-\text{NO}_2$.

The dyes used herein are by virtue of their dual purpose modified cyanines. Dyes of this general type are elucidated in the literature and the procedures for synthesis of compounds of this type are well-known to those skilled in the art. Many current processes, for example, for the formulation of cyanine dyes use condensation type reactions. These reactions, shown in "Mees, C.E.K., *The Theory of the Photographic Process*, The Macmillan Co., New York, 1954," utilize an active hydrogen on one reactant and an active negative atom (halogen, cyano, alkyl or aryl mercapto, alkoxy,

anilino, or acetanilido) on the other reactant. Condensing agents are used as scavengers and to shift the reaction equilibrium in the desired direction. The intermediates used in the preparation of conventional sensitizing dyes, and the condensing agents, including their preparative procedures, are discussed in "Glafkides, P., *Photographic Chemistry*, Vol. I and II, Fountain Press, London, 1960" starting on page 753.

Typically, the dyes described in this patent application can be prepared by the two following exemplary approaches, depending upon the substituents in the dye intermediates:

a. By condensation of appropriately substituted guanidines with intermediates containing negative active atoms in the desired positions: and

b. by formation of the appropriately substituted guanidine structure in situ via the reaction of the substituted carbodiimide with amino groups located in the dye intermediate.

Coordinate structures such as 1, 2, and 3, may therefore, for example, pursuant to approach a as set forth above, be prepared by the following type of flow process:

In many instances the substituted aromatic amine and the Negative Atom Substituted Intermediate are commercially available compounds.

The flow process above set forth is now illustrated in the course of preparing the structure (3):

EXAMPLE 1

I. Preparation of N,N' bis (4-hydroxyphenyl) thiourea:

Equations:

Preparation:

In a 300 ml balloon flask, place 50 ml (39.57g) anhydrous methyl alcohol, 6 ml (7.6g) carbon disulfide (Baker 9172), 21.8g p-aminophenol (Eastman Kodak P362), and 1.5g Potassium Hydroxide (Baker 3140). An exothermic reaction may occur which will require cooling to contain the reactants. After the initial reaction subsides, attach electric heating mantle and water cooled condenser, reflux the mixture for 8 hours. Distill off the excess alcohol and CS_2 . Wash residue with warm water to remove residual KOH and unreacted p-

aminophenol. Filter, wash with warm water, and dry. Purify by recrystallization, desolving the residue under reflux in boiling rectified spirits (ethanol). Filter in heated funnel if the solution is not clear. Add hot water until the solution becomes cloudy, cool, and filter.

Additional information respecting this reaction I may be found at:

Fusion, *Organic Chemistry*, John Wiley & Sons Inc., New York 1942 p.415; Brewster, *Organic Chemistry*, Prentice-Hall, New York, 1948 p.553; Smith, *The Chemistry of Open Chain Organic Nitrogen Compounds*, vol 1, W.A. Benjamin Inc., New York 1965 p.276; Wertheim, *Practical Organic Chemistry : A Laboratory Manual*, McGraw-Hill, New York, 1953 p.642.

EXAMPLE 2

II. Preparation of N,N' bis (4-hydroxyphenyl) guanine

Equations:

Preparation:

In a 500 ml two necked balloon flask, place 100 ml (87.9g) dry benzene (BA 9154), 20g anhydrous magnesium sulfate (BA 2506), 44g mercuric oxide (BA 2620), a gas dispersion tube with fritted disc or cylinder is introduced into the mixture through one neck of the flask. Anhydrous ammonia gas is allowed to bubble through the mixture saturating the solvent. Add 26g of N,N' bis (4-hydroxyphenyl) thiourea (from preparation I) and install a water cooled condenser in the other neck of the flask. Continue the flow of ammonia gas. Attach an electric heating mantle and reflux the mixture for 6-8 hours with continuous flow of ammonia. Note: the reaction mixture must be saturated at all times with ammonia gas as the intermediate carbodiimide will, if allowed, react with the hydroxyl groups reducing the yield of guanidine. Filter to remove sulfides and drying agent, distill off excess benzene, and dry. Purify by recrystallization from dry benzene.

EXAMPLE 3

III Guanidine synthesis of a Merocyanine dye:
 Condensation product of N,N' bis (4-hydroxyphenyl) guanidine and 2,5-dichloro-p-benzoquinone

Equations:

Preparation:

In a 500 ml balloon flask, mix 100 ml (78.9g) anhydrous methanol, 24.3g N,N' bis (4-hydroxyphenyl) guanidine (from preparation II), 8.9g 2,5-dichloro-p-benzoquinone (EK 4410), 6g Magnesium oxide (BA 2477). Attach water cooled condenser, electric heating mantle, magnetic stirring unit, and reflux the mixture for 2 hours. Filter to remove solids, distill off alcohol, wash residue with distilled water and dry. Purify by recrystallization from dry ethanol.

The formation of silver or silver halide salts of these dyes follow the conventional methods currently in use in the manufacture of silver halide film. These processes involve the introduction of silver nitrate into the mixture and subsequent introduction of soluble halide salts (KI , KBr , KCl , NaI , $NaBr$, $NaCl$) followed by washing with water.

Additional information respecting this reaction III may be found at:

I.G. Farbenindustrie, BIOS 1482, p. 23 (PB86136);
 I.G. Farbenindustrie, *ibid.*, p. 26; Glafkides, Pierre, *Photographic Chemistry*, Fountain Press, London 1958 Chapter XXVIII pp. 298-326. Omitting, for purposes of simplification, the complexed heavy metal ion — such as silver — we may illustrate by structure (4), the manner in which stress introduced by heat or alkaline conditions effects fracture of the guanidine-like

group:

The dotted lines in (6) represent the characteristic manner in which the said guanidine-like group fractures, and it is thus evident from equation (6) why structures such as (4) can serve as color sensitizer, sensitive media, and developing agent, without the need for conventional development solutions.

In accordance with the present invention, the photo-sensitive layer utilized on an imaging member will typically include silver ion derived from $AgNO_3$ or AgX (Br , Cl , I), a hygroscopic agent, a light sensitive structure of the type (1), and a binder which preferably will be other than gelatin; e.g., polyvinyl alcohol or other permeable synthetic plastic. The said formulation is typically coated upon a plastic or baryta coated paper substrate.

In accordance with the invention, processing of members thus prepared, is typically a simple three-step process involving: (1) developing by convenient heating means, including, e.g., radiant heat (such heating typically raising the member to a temperature of the order of 100° to $200^\circ C$.) and/or treating with buffered alkaline water (pH of the order of 10 to 13); (2) washing and stopping; and (3) fixing, e.g., with conventional silver solvent hypo.

While the present invention has been particularly set forth in terms of specific embodiments thereof, it will be appreciated in view of the instant disclosure, that numerous variations upon the present invention are now enabled to those skilled in the art, which variations are yet, in propriety, within the scope of the instant teaching. Accordingly the invention is to be broadly construed, and limited only by the scope and spirit of the claims now appended hereto.

I claim:

1. A method for photographic imaging, comprising:
 a. exposing to a light pattern a sensitized layer containing cyanine dye coordinate structures of the type:

where n is an integer, M is a silver ion, at least D is a photographic developer structure, and D' is a structure which does not dye couple with oxidized fragments D split from said dye coordinate structure, actinic wavelengths present in said light acting to reduce said metal ions and partially oxidize at least D ;

b. disrupting the chemical bonds joining said developer structures and amino group to said dye, to enable image development at points in said layer struck by said light; and
 c. removing unreacted metal ion and metal complexes from said layer.

2. A method in accordance with claim 1 wherein D' is further a photographic developer structure, said light acting in addition to partially oxidize D'.

3. A method in accordance with claim 2, wherein D is selected from the group consisting of para amino phenols and para phenylene diamines, and D' is an oxidized para dihydroxy benzene.

4. A method in accordance with claim 1, wherein said chemical bonds are disrupted by treating said layer with an aqueous alkaline solution.

5. A method in accordance with claim 1, wherein said chemical bonds are disrupted by heating said layer.

6. A member for photographic recording of a light image pattern, comprising:

- a. a support substrate; and
- b. a binder layer coated upon said substrate containing cyanine dye coordinate structures of the type:

20

25

30

35

40

45

50

55

60

65

where n is an integer, M is a silver ion, at least D is a photographic developer structure, and D' is a structure which does not dye couple with oxidized fragments D split from said dye coordinate structure, said dye being chosen to be sensitive to said light, actinic wavelengths present in said light acting to reduce said metal ions and partially oxidize at least D, whereby disruption of the chemical bonds joining said developer structures and amino groups to said dye enables image development at points in said layer struck by said light.

7. A member in accordance with claim 6 wherein D' is further a photographic developer structure, said light acting in addition to partially oxidize D'.

8. A member in accordance with claim 7, wherein D is selected from the group consisting of para amino phenols and para phenylene diamines, and D' is an oxidized para dihydroxy benzene.
